UNITED STATES PATENT OFFICE.

FRANCIS J. McLOUGHLIN, OF BROOKLYN, NEW YORK.

TURNSTILE.

Application filed March 6, 1925. Serial No. 13,427.

The present invention has relation to a novel and improved form of turnstile of the general type extensively used in fairs, railway depots, and platforms, etc., either for 5 permitting passage of persons in one direction only or for registering the number of passengers passing in one or both directions, or for both purposes. In some cases these turnstiles are made to oppose passage in one 10 or both directions until unlocked, usually by means operated by the dropping of a coin. My present invention is adapted for use in any of these ways.

The turnstiles hitherto in general use involve the use of a bar or bars which extend across the passageway to be commanded and are swivelled upon a support at one side in such a manner as to revolve around such support in a horizontal plane or planes. In devices of such a character it is clear that room 20 must be provided upon both sides of the support upon which the bars are mounted, thus making it necessary to provide, in addition to the space required for passage of a person and 25 for the support, an additional space equal to that provided for the person passing, wherein the bar or bars may swing around the support.

The object of the present invention is to 30 provide a practical form of two-armed turnstile so mounted and constructed that the bars, when not in position across the passage, occupy a substantially vertical position, thereby accomplishing a great saving in the 35 span necessary to be provided for each passage to be controlled.

The invention is illustrated in a preferred 40 form in the accompanying drawings wherein Figure 1 is a front elevation of one form of the device partly broken away, Figure 2 is a plan view of the same showing the position after preliminary tilting of the arms, Figure 3 is a vertical sectional view taken on the line 3—3 in Figure 1, Figure 4 is a partial 45 plan-view as in Figure 2, but with a portion broken away, Figure 5 is a perspective view of the steadyng cam, Figure 6 is a side elevation of the top of the main support with a portion broken away and partly in vertical 50 section, Figure 7 is a vertical sectional view of an example of a coin control which may be used with the invention, Figure 8 is a sectional view on the line 8—8 in Figure 6, and Figure 9 is a view similar to Figure 7 showing 55 a different position of the parts.

Fundamentally the invention comprises

two arms at substantially right angles connected together and adapted to revolve in planes at right angles to each other, as on a universal joint. To accomplish this I prefer to provide a main axle and a swivel mounted thereon at right angles thereto. The arms, being mounted upon the swivel, are supported on the main axle, which last may be supported at either or both ends. In 60 the preferred form shown, the axle is supported at both ends. For purposes of convenience I shall hereinafter refer to movement of the arms around the main axle as a "tilting" movement and to movement around 65 the swivel as a "swinging movement."

In the specific form of the invention herein shown the main axle 10 is shown revolvably mounted at one end in the supporting casing 11, and at the other end in the secondary 75 support or post 12. The casing 11 may be used for accommodating counting means or locking means, etc., and I have indicated herein, as a mere example, a coin controlled lock, hereinafter described. The turnstile 80 may, of course, be constructed to be pushed in either or both directions without departing from the scope of the invention.

As shown in Figure 3, the main axle is 85 preferably made hollow, and upon it is mounted at right angles a shaft 13, which I shall call the "swivel". Within the shaft 10, there is mounted upon the swivel a square abutment piece 14 to receive the pressure of the steadyng spring, as hereinafter described. 90

The turnstile arms 15 and 16 are mounted upon a hollow hub 17 which is revolvably mounted upon the ends of the swivel 13, and these arms preferably extend inward, as shown so that the inner end of each arm 95 when in vertical position will abut against the main shaft 10 to form a stop against swinging around the swivel, when in normal position.

The steadyng devices for controlling and 100 regulating the action of the arms under the influence of a simple forward push exerted by a person passing through the gate are preferably constructed as follows.

There is fixed on the main supporting cas- 105 ing 11 an annular cam 18 shown in perspective in Figure 5. This cam surrounds the main axle 10 and is concentric therewith.

The main axle 10 is slotted as at 19 (see 110 Figure 1), and through this slot there extends, at right angles to the axle 10, a shaft 20 bearing wheels 21 at its opposite ends,

which wheels bear normally upon the annular face of the cam 19 being pressed against the cam by the spring 22 which bears at its opposite end on the abutment 14. When the 5 stile is in normal position, as in Figure 1, these wheels rest within the depressions 23, which are so formed as to offer a material resistance to any effort tending to drive the wheels out of them along the face of the cam. 10 This keeps the turnstile steady in place when not in use, but, upon pressure being exerted on one of the arms, as hereinafter described, this resistance is overcome, the 15 wheels being allowed to leave the depressions 23 by the yielding of the spring 22.

The interior surfaces of the two sides of the hub 16 are furnished with inclined planes 24 one end of each of which bears (or nearly bears) upon the corresponding wheel 21, when in idle position as in Figure 1, so as to oppose any swinging of the arms around the shaft 13.

Within the supporting casing 11, the shaft 10 (or a hub thereon) is provided with 25 diametrically opposite stops 25, arranged so that, when the axle 10 is tilted through ninety degrees (as hereinafter described) one stop comes up against the end of a pivoted lever 26 (see Figure 6). For greater 30 solidity I prefer to provide an abutment 27 fixed to the inside of the casing 11, behind a projection at the end of the lever 26. This abutment takes the thrust of the stop 25, and relieves the pivot on which the lever 26 35 is mounted.

The normal operation of the arms is as follows:

The first thrust exerted by a person passing through tilts the arms into the position 40 shown in Figure 2, where this tilting is stopped by the stop 25 striking the lever 26 as shown in Figure 6. This action has caused the wheels 21 to ride up the inclined portions 28 of the cam 18, and has brought 45 them onto the raised flat portions 29.

As shown in Figure 2, this brings the wheels 21 into such a position in relation to the planes 24 that, when the arms 15 and 16 and hub 17 are swung around the swivel 13, 50 these planes press the wheels 21 to the right against the spring 22, and thus the pressure of this spring exerts a steady pressure upon the arms during the subsequent operation. This action is illustrated in Figure 4.

55 The tilting action being completed, further pressure upon an arm 15 causes swinging of the two arms as indicated by the arrows in Figure 2, and, as soon as the planes 24 have passed beyond the right angle position with respect to the axle 10, the pressure 60 of the wheels 21 upon these planes will tend to continue the swinging action until the arms assume the position shown in dotted lines in Figure 2 (the person pushing having passed through).

During this last movement, the curved surface of the hub 17, passing over the knob 30 pushes inward the lever 31 pivoted at 32 (see Figure 8). The upper end of this lever 70 31 has a curved arm 33 which lifts the stop 26, freeing the stop 25, and the weight of the forward arm 15 then causes the arms and hub to tilt through ninety degrees again, thus bringing the arms back into the normal 75 position. Of course, in this operation the two arms have exchanged positions, the apparatus being in a new normal or idle position, as shown in Figure 1. During this last tilting movement, the spring pressed wheels 21, acting on the inclined parts 28 of the 80 cam 18, assist in completing the operation.

In Figures 1, 7, and 9, I have shown a simple and elementary coin-controlled lock as an example of a device of this kind applied 85 to my turnstile.

A hub 34, fixed to the axle 10, has a flange or rim 35 provided with a locking notch 36 adapted to be engaged with a pivoted stop 37 to prevent reverse movement of the stile. This may be used with or without the coin 90 control.

Where the coin control is used, there is a pocket having sides notched as at 38, so that, when the pocket is empty, forward movement of the axle 10 and hub 34 is prevented 95 by the pivoted stop lever 39. In the normal or idle position, a coin chute 40 extends above the pocket, and a coin may be dropped into said pocket as shown in Figure 7. As shown in dotted lines in Figure 7, the presence of this coin will prevent the stop lever 39 from falling into the notches 38 when the hub 34 is turned as shown by the arrow, thus permitting the complete operation of the turnstile as already described. As shown, the notches and pockets are duplicated, to correspond to the two diametrically opposed 100 idle positions of the axle 10.

Various changes can be made in this apparatus without departing from the scope 110 of the invention which is not limited to the details herein shown and described.

What I claim is—

1. A turnstile having two arms fixed at right angles to each other and adapted to lie normally in a common vertical plane; in combination with a movable mounting for said arms placed at their junction and adapted to permit said arms to exchange positions through a single uninterrupted movement.

2. Apparatus as in claim 1 wherein the mounting is adapted to permit a pivotal movement in two planes at right angles to each other.

3. Apparatus as in claim 1 wherein the mounting comprises a swivel carried by an axle at right angles thereto.

4. In a turnstile, a main axle, a support thereon, a swivel on the axle and two arms 130

mounted to swing on said swivel, said arms being adapted to bear against said axle one at a time to prevent accidental swinging in one direction with the arms in normal position.

5. In a turnstile, a support, a main axle horizontally mounted thereon, arms adapted to be tilted on said axle and a stop to limit the tilting movement of said arms.

10. 6. In a turnstile, a support, a main axle horizontally mounted thereon, a swivel on said axle, arms adapted to be tilted on said axle and to swing on said swivel and a lock to limit the tilting movement of said arms adapted to be released automatically by a swinging movement of the arms on said swivel.

7. In a turnstile, a support, a revolute axle thereon, a stop on the axle, a pivoted 20 stop lever for said stop, arms adapted to swing on and tilt with said axle, and means adapted to be operated by swinging movement of the arms on the axle for releasing said stop lever.

25. 8. In a turnstile, a support, a revolute axle thereon, a hub pivotally mounted on the axle, arms carried by said hub, a stop on said axle, a pivoted stop lever for said stop and means adapted to be actuated by 30 contact with said hub to move said stop lever and release said stop.

9. In a turnstile, a support, a main axle thereon, a swivel on the axle, two arms adapted to swing on said swivel, a spring

on the main axle, and assisting means actuated by said spring adapted to push said arms through a portion of their swinging movement.

10. Apparatus as in claim 9, wherein the assisting means comprise a spring-pressed 40 wheel and an inclined plane carried by the arms and adapted to bear on said wheel.

11. In a turnstile, a support, a horizontally revolute axle thereon, a hollow hub pivotally mounted on the axle, arms carried by 45 said hub, a spring-pressed wheel on the axle, and an inclined steady plane fixed within the hub and adapted to press against said wheel when the hub is swung on its pivot.

12. In a turnstile, a support, a hollow slotted main axle thereon, a shaft passing through the slots therein, wheels on the ends of said shaft, a cam fixed on the support, and a spring within the axle adapted to 50 press said wheels against said cam.

13. In a turnstile, a horizontal main axle, two arms fixed at right angles to each other and pivotally mounted on said axle, and a coin-controlled lock for governing operation of said axle.

14. In a turnstile, a support, two arms fixed at right angles to each other, a revolute axle on said support, and a mounting for said arms carried by said axle and adapted to swing thereon.

In testimony whereof I have hereto affixed my signature.

FRANCIS J. McLOUGHLIN.
